UNITED STATES PATENT OFFICE

151,983

DESIGN FOR A COMBINATION HASSOCK AND COFFEE TABLE

Gabriel C. Guertin, Boston, Mass.

Application April 10, 1947, Serial No. 138,280

Term of patent 3½ years

(Cl. D15—8)

To all whom it may concern:

Be it known that I, Gabriel C. Guertin, a citizen of the United States, residing at Boston, in the county of Suffolk and Commonwealth of Massachusetts, have invented a new, original, and ornamental Design for Combination Hassock and Coffee Table, of which the following is a specification, reference being had to the accompanying drawing, forming part thereof.

In the drawings,

Fig. 1 is a perspective view of a combination hassock and coffee table showing my new design, and

Fig. 2 is a similar view showing the coffee table extended from the hassock.

The sides of the hassock body not shown in the drawing are identical with the sides shown in Figs. 1 and 2.

I claim:

The ornamental design for a combination hassock and coffee table, substantially as shown and described.

GABRIEL C. GUERTIN.
